CLAIM

USPC **D8/70**

(58) **Field of Classification Search**

The ornamental design for a polishing pad, as shown and described.

USPC D8/20, 61, 62, 63, 70; D32/35, 40, 42;
D15/124, 125, 126, 132, 138, 139, 140

DESCRIPTION

CPC B24D 9/08; B24B 55/102
See application file for complete search history.

(56) **References Cited**

FIG. 1 is a perspective view of the polishing pad in accordance with the present invention;

U.S. PATENT DOCUMENTS

FIG. 2 is a workpiece-facing plan view of the polishing pad shown in FIG. 1;

2,225,193 A	12/1940	Benner
2,425,368 A	8/1947	Doermann
3,121,982 A	2/1964	Miller
3,464,166 A	9/1969	Bouvier
3,517,466 A	6/1970	Bouvier
3,823,516 A	7/1974	Christian
3,934,377 A	1/1976	Tertinek
4,271,557 A	6/1981	Caron
4,502,174 A	3/1985	Rones
4,724,567 A	2/1988	Rones
5,054,245 A	10/1991	Coty

FIG. 3 is an opposite plan view from that of FIG. 2 of the polishing pad shown in FIG. 1; and,

FIG. 4 is a side elevation view of the polishing pad shown in FIG. 1.

The broken lines form no part of the claimed design. The pattern designations shown in the figures are not intended to claim the specific patterns or materials but are instead intended to claim that the appearance of the outer ring (e.g., FIGS. 1 and 2) is different than the appearance of the center and backside of the polishing pad (e.g., FIGS. 1-3).
